UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

GUN.

1,240,988.

Specification of Letters Patent. Patented Sept. 25, 1917.

Application filed September 18, 1916. Serial No. 120,761.

To all whom it may concern:

Be it known that I, CHARLES F. LEFEVER, a citizen of the United States of America, residing at Plymouth, in the county of 5 Wayne and State of Michigan, have invented certain new and useful Improvements in Guns, of which the following is a specification, reference being had therein to the accompanying drawings.

10 The invention relates to guns and more particularly to air guns, and the invention comprises the novel construction as herein-after set forth.

In the drawings:

15 Figure 1 is a longitudinal section through a portion of a gun barrel provided with my improved magazine construction;

Fig. 2 is a similar view showing the magazine in position for loading;

20 Fig. 3 is a perspective view of the magazine with the gun barrel removed;

Fig. 4 is a cross section on line $\alpha-\alpha$ Fig. 1.

A is the false barrel and B is the true or shooting barrel arranged therein. C is an 25 abutment for the piston arranged at the rear end of the true barrel B.

It is usual to provide a detachable connection between the true barrel and the spring abutment, and where a magazine is 30 used, to provide a guide for directing the shot therefrom into the true barrel. With the present invention I have simplified the construction by attaching the true barrel to the abutment and the latter to the air compression cylinder, forming a unit engageable 35 as such with the false barrel. I have also simplified the construction of the connection between the magazine and the true barrel, utilizing the abutment as a guide and 40 forming the latter of a concave or dish-shaped construction. Still another feature of the invention is the means employed for loading the magazine and for placing a tension on the follower.

45 In detail, the abutment C is formed with the concave or dished outer face D and is attached to the inner end of the air cylinder E. The true barrel B is also attached to the abutment and projects forward therefrom. F is a 50 magazine barrel arranged parallel to the true barrel within the circumference of the abutment C. G is a strap for attaching the magazine barrel to the true barrel adjacent to the abutment C, this being prefer- 55 ably secured by soldering or equivalent

means. The adjacent sides of the magazine barrel and true barrel are cut away for the passage of shot from the one to the other, and the strap G together with the concave face of the abutment C forms a guide for 60 the transfer.

To feed the shot from the magazine to the true barrel it is necessary to provide a follower, which must be retracted when the magazine is to be re-loaded. A spring is 65 also required for yieldably pressing upon the follower and it is usual to place this spring under compression when the follower is retracted. I have devised an improved construction in which the spring is inclosed in a telescopic extension of the magazine barrel and is capable of being drawn outward when the magazine is to be re-loaded. This will retract the plunger without compressing the spring, but after the loading 70 of the magazine the movement of the telescopic extension inward will compress the spring and maintain the necessary tension on the follower. As shown, H is the telescopic extension, which is sleeved around the magazine barrel F, and houses the spring I for the follower J. The latter remains in engagement with the magazine barrel, but when the barrel H is drawn outward said plunger will be sufficiently retracted to uncover registering apertures K and K' in the false barrel A and magazine F. This will permit of introducing the shot 75 into the magazine and when the latter is full the movement inward of the barrel H will compress the spring I and also will cover the aperture K', preventing the falling out of the shot. The barrel H is prevented from complete disengagement from the barrel F by stops L thereon, and these 80 stops also prevent disengagement of the follower J from the barrel F. M is a catch for locking the barrel H in its normal position, said catch being released by a thumb piece N.

With the construction described in use the magazine may be readily loaded by drawing outward the barrel H. This movement will withdraw the follower J beyond the registering apertures K and K' but will not disengage it from the end of the barrel F. The spring I is also held from disarrangement by being housed within the withdrawn barrel H. The inward movement of the barrel H will 85 place the spring under compression, so that 90

the shot within the magazine will be fed inward as fast as they are transferred to the shot barrel. The transfer of the shot from the magazine to the true barrel is effected by 5 the guidance of the concave abutment C and the surrounding strap G.

What I claim as my invention is:

1. In a gun, the combination with a false barrel, of an air compression cylinder insertible therein, a piston abutment having a concave outer face, a true barrel engaging said piston abutment, a magazine barrel arranged parallel to said true barrel and cut away at its inner end for the transfer of 15 shot therefrom to said true barrel, said transfer being guided by the concave face of said abutment.

2. In a gun, the combination with a false barrel, of an air compression cylinder insertible therein, a piston abutment secured to the end of said cylinder and provided with a concave outer face, a true barrel secured to said piston abutment, a magazine barrel arranged parallel to said true barrel, 25 and a strap embracing said magazine barrel and true barrel adjacent to said abutment, said magazine and true barrel being cut away at their adjacent inner ends for the transfer of shot from one to the other, said 30 transfer being guided by said strap and concave face of the abutment.

3. In a gun, the combination with a false barrel, of a true barrel therein, a magazine barrel arranged between said true barrel and false barrel, a barrel sleeved upon said magazine barrel to telescopically engage the same, being endwise withdrawable from said false barrel, a follower and a spring within said magazine barrel, the tension of said 40 spring being relieved and the follower retracted by the endwise withdrawal of the telescopic sleeve.

4. In a gun, the combination with a false barrel, of a true barrel therein, a magazine barrel arranged between said false barrel and true barrel and parallel thereto, a tube sleeved upon said magazine barrel, telescopically engaging the same and endwise withdrawable from said false barrel, a follower within said magazine barrel, a spring for yieldably pressing said follower toward the inner end of said barrel, the outer end of said spring being anchored in the tubular sleeve, to be withdrawn outward therewith, and a stop for limiting the outward 55

movement of said sleeve at a point where said follower is still within the magazine barrel.

5. In a gun, the combination with a magazine barrel, having a discharge aperture at one end thereof and a fill aperture adjacent to the opposite end, of a tube sleeved about said magazine barrel and telescopically movable thereon, a follower within said magazine barrel, a spring for yieldably pressing said follower toward the inner end of said magazine barrel, the outer end of said spring being anchored in said tubular sleeve, whereby the outward withdrawal of said sleeve will retract said plunger and uncover the feed aperture into said magazine barrel, and the inward movement of said sleeve will place a tension on the spring and close the feed aperture, and a stop for limiting the outward withdrawal of said sleeve. 70

6. In a gun, the combination with a false barrel and a true barrel therein, of a magazine barrel arranged between said false barrel and true barrel, having a discharge opening at its inner end and a feed opening intermediate its ends, a tube sleeved upon said magazine barrel and endwise withdrawable from said false barrel, a follower within said magazine barrel, a spring for said follower, having its outer end anchored in said tubular sleeve, and a catch for holding said tubular sleeve from endwise movement. 80

7. In a gun, the combination with a false barrel, of a true barrel therein, a magazine barrel in between said true barrel and false barrel, the inner end of said magazine barrel having a discharge aperture communicating with said true barrel and being also provided with a feed aperture intermediate its ends in registration with a feed aperture through said barrel, a tubular sleeve surrounding said magazine barrel, closing the registering feed apertures in the same and said false barrel, said tube being endwise withdrawable to uncover the said registering apertures, a catch for holding said sleeve in its inner position, a follower in said magazine barrel, and a spring for yieldably pressing said follower toward the inner end of said barrel, the outer end of said spring being anchored to said tubular sleeve and being withdrawable therein during the outward movement thereof. 90

In testimony whereof I affix my signature.

CHARLES F. LEFEVER.
